DESIGN FOR A CONDUIT RECEPTACLE

Joseph F. O'Brien, Jersey City, N. J.

Application April 19, 1941, Serial No. 100,519

Term of patent 14 years

To all whom it may concern:

Be it known that I, Joseph F. O'Brien, a citizen of the United States of America, residing in Jersey City, county of Hudson, and State of New Jersey, have invented a new, original, and ornamental Design for a Conduit Receptacle, of which the following is a specification, reference being had to the accompanying drawing, forming part thereof.

In the drawing:

Fig. 1 is a front perspective view of a conduit receptacle showing my new design.

Fig. 2 is a side elevation of the conduit receptacle shown in Fig. 1.

Fig. 3 is a front elevation of the conduit receptacle shown in Fig. 1.

I claim:

The ornamental design for a conduit receptacle, substantially as shown.

JOSEPH F. O'BRIEN.
